HOLDER FOR SAFETY RAZOR BLADES

Filed July 8, 1949

UNITED STATES PATENT OFFICE

2,543,096

HOLDER FOR SAFETY RAZOR BLADES

Frederick W. Dierdorf, Castile, N. Y.

Application July 8, 1949, Serial No. 103,725

4 Claims. (Cl. 30—334)

1

This invention relates to an improved razor or blade holder for detachably mounting a safety razor blade and more particularly has reference to a novel construction of holder similar to a conventional straight razor wherein in lieu of a conventional straight razor blade the holder or razor is provided with a mounting structure for detachably mounting a safety razor blade therein and which will effectively function to positively retain the safety razor blade against any movement relatively to the blade holder while in an applied position but which is capable of being quickly and easily detached from the blade holder or mounting for replacement.

Another object of the invention is to provide a razor having a blade holder or mounting means of extremely simple construction.

A further object of the invention is to provide a razor of a construction similar to a conventional straight razor and which is readily adapted for use by barbers and others desiring or preferring the type of razor known as a "straight" razor yet which eliminates the need for continuously sharpening the blade by providing a blade holder or mounting from which a conventional type safety razor blade may be quickly and easily removed and replaced when it becomes dull.

Various other objects and advantages of the invention will hereinafter become more fully apparent from the following description of the drawing, illustrating a presently preferred embodiment thereof, and wherein:

Figure 1 is a side elevational view showing the improved razor in a partially opened position and with a safety razor blade securely held therein;

Figure 2 is an enlarged longitudinal sectional view of a portion thereof taken substantially along a plane as indicated by the line 2—2 of Figure 1;

Figure 3 is a view partly in section and partly in side elevation taken substantially along a plane as indicated by the line 3—3 of Figure 2;

Figure 4 is a longitudinal sectional view, partly in side elevation taken through the blade holder with the blade and blade retaining member removed, and

Figure 5 is a cross sectional view through the blade holder or mounting taken substantially along a plane as indicated by the line 5—5 of Figure 3.

Referring more specifically to the drawing, the novel razor in its entirety is designated generally 6 and includes a handle, designated generally 7 formed by corresponding side members 8 which are mounted in spaced substantially parallel re-

2

lationship to one another by a spacing block 9 which is located between corresponding ends thereof and which is secured thereto by a headed fastening 10.

6 The blade holder, designated generally 11 of the razor 6, includes an elongated shank portion, designated generally 12 and which substantially corresponds in shape with the shank of a straight razor blade. The shank portion 12 has a portion, 10 spaced from its shank end, disposed between the side members 8, near their opposite ends and which portion is connected to said side members 8 by a headed fastening 13 which is rotatably engaged by the shank 12 for pivotally connecting 15 the blade holder 11 to the handle 7. The shank end 14 of the shank 12 projects in one direction beyond the handle 7, similar to the shank end of a straight razor blade and is adapted to be engaged by the little finger when the razor 6 is in use, so that said razor may be held in the same manner as a straight razor.

The blade holder or mounting 11 includes an elongated substantially rigid metal strip or bar which is folded upon itself intermediate of its 25 ends as seen at 15 to provide spaced substantially parallel bar portions or plies 16, portions of which constitute parts of the shank 12. A spacing bar 17 is disposed between the bar portions 16 and is secured thereto by spaced rivets or other fastenings 18. The spacing bar 17 combines with contiguous portions of the bars or plies 16 to form the shank 12 and extends from the shank end 14 to a point spaced from the intermediate bar portion 15. The bar portions 16 and 17 are 30 of the same width except that the end of the bar 17, located remote to the pivot 13 and adjacent the intermediate bar portion 15, is laterally enlarged as best illustrated in Figures 3 and 4 to define an upwardly extending flange portion 19 and a depending flange portion 20. If desired, the flange portions 19 and 20 and the part of the bar 17 located therebetween may constitute a 35 separate element from the remainder of the bar 17. The intermediate bar portion 15 and the portions of the bar members 16 located between said intermediate portion 15 and the adjacent end of the spacing bar 17 combine to form an elongated loop 21, the elongated slot or opening 22 of which is adapted to accommodate a portion 40 of the blade 23 of a safety razor blade which also includes a head 24 which is formed by an elongated metal strip which is folded lengthwise and clamped around the back edge of the blade 23, as best seen in Figure 5. The upper edges of the bar 45 portions 16, constituting part of the loop 21 are 50 55

preferably downwardly offset beyond the flange 19, as seen at 25, and said upper edges 25 are adapted to provide seats for abutting engagement with the two longitudinally extending edges of the blade head 24, as best seen in Figure 5, for supporting the blade 23 in the blade holding loop 21 and so that its cutting edge 26 will be disposed at the same level as the outer edge of the bottom flange 20, as clearly illustrated in Figure 3, so that said flange edge will function as a guard or shield for the inner end of the cutting edge 26.

It will be readily apparent that the blade 23 may be quickly and easily applied to the blade holder loop 21, as illustrated in the drawing and as previously described, and that the blade head 24 will prevent the blade 23 from moving downwardly through the loop 21 beyond its position as illustrated in Figures 1 and 3. The blade 23 is likewise held detachably in the blade holding loop 21 by a retaining member 27 comprising a strip of metal which is folded upon itself lengthwise and intermediate of its longitudinal edges and which has inturned longitudinal edge portions 28 defining a narrow slot 29 therebetween and which extends from end-to-end thereof. The corresponding sides 30 of the blade retaining member 27 are of a width so that when its intermediate folded or closed edge 31 is in engagement with the outer edge of the blade head 24 and the outer edge of the top flange 19, its inturned edges 28 will engage the bottom edges of the blade holding loop 21, as clearly seen in Figure 5. When the blade 23 is applied to the blade holding loop 21, the upper edge of its head 24 is disposed in the same plane as the outer edge of the top flange 19 and as the blade retaining member 27 is open at each end thereof it will be readily apparent that said retaining member 27 can be slid over the blade holding loop 21 and the blade head 24 and upper flange 19 so that the blade 23 will depend from the holder 21 through the slot 29 of the retaining member 27 and will be held against upward displacement by the retaining member 27 which is retained against upward displacement by its inturned edge portions 28 engaging under the loop 21. Likewise, the blade 23 is held against longitudinal displacement by the intermediate bar portion 15 at one end and by the adjacent end of the spacer bar 17 and the flanges 19 and 20. It will thus be readily apparent that the blade 23 will be securely maintained against any movement relatively to the blade holding loop 21 while the retaining member or clip 27 is applied to afford the maximum of safety to the user; however, by merely sliding the retaining member 27 off of the outer end of the loop 21, the blade 23 may be quickly removed from the blade holding loop and replaced by a new blade.

It will thus be seen that a straight-type razor has been provided but which is equipped with a replaceable wafer-thin safety type blade so that a dull blade can be quickly and easily removed and replaced to thereby eliminate the need for frequently sharpening the razor as is required with conventional straight razors. However, the razor 6 can be utilized for all purposes of a straight razor, as for example by barbers who require a straight razor for properly shaving a customer around the ears after cutting the hair.

Various modifications and changes are contemplated and may obviously be resorted to, without departing from the spirit or scope of

the invention as hereinafter defined by the appended claims.

I claim as my invention:

1. A razor comprising an elongated handle having a slot extending from one end to adjacent the other end thereof, an elongated blade holder having a shank constituting one end thereof, an intermediate portion of said shank extending through said handle near its slotted end and being pivotally connected thereto for swingably mounting the blade holder on the handle, a safety razor blade including a cutting edge, a back edge and a blade head enclosing the back edge and extending outwardly from opposite sides of the blade and secured thereto, said shank having an elongated loop defining its opposite end and provided with closed ends, an open top and an open bottom, said loop having an elongated opening or slot extending from end-to-end thereof and from its open top to its open bottom detachably receiving the safety razor blade therein, the closed ends of said loop engaging the ends of said blade for holding the blade against longitudinal movement therein, said blade holding loop having substantially parallel side portions provided with transversely aligned upper edges engaging the head of the blade for supporting the blade in the loop and with the cutting edge of the blade disposed below the loop and substantially parallel to the bottom edge thereof, and an elongated blade retaining member having open ends, spaced substantially parallel sides, a closed longitudinal edge and a restricted open longitudinal edge for slidably and detachably engaging over the blade holder loop and blade head, said blade retaining member having its closed edge engaging the outer edge of said blade head and its restricted opening disposed beneath the blade holding loop and accommodating a portion of the blade therein, said blade portion being spaced from the cutting edge of the blade, and portions of said blade retaining member, disposed at either side of said restricted opening, engaging the bottom edge of the blade holding loop to retain said blade retaining member against upward displacement relatively to the blade holding loop.

2. A razor as in claim 1, said blade holder including an elongated bar folded upon itself intermediate of its ends, a spacing bar disposed between complementary portions of said folded bar and secured thereto and combining therewith to define the blade holder shank and having one end thereof defining the inner end of the blade holding loop, the remainder of said blade holding loop being formed by the intermediate portion of said folded bar.

3. A razor as in claim 1, said blade holder including an elongated bar folded upon itself intermediate of its ends, a spacing bar disposed between complementary portions of said folded bar and secured thereto and combining therewith to define the blade holder shank and having one end thereof defining the inner end of the blade holding loop, the remainder of said blade holding loop being formed by the intermediate portion of said folded bar, and said spacing bar having a laterally enlarged end located adjacent said blade holding loop and including a depending flange extending downwardly from the shank for engaging one end of the blade adjacent its cutting edge and having an upwardly extending flange for engaging said end of the blade head.

4. A razor as in claim 1, said blade holder including an elongated bar folded upon itself

intermediate of its ends, a spacing bar disposed between complementary portions of said folded bar and secured thereto and combining therewith to define the blade holder shank and having one end thereof defining the inner end of the blade holding loop, the remainder of said blade holding loop being formed by the intermediate portion of said folded bar, and said spacing bar having a laterally enlarged end located adjacent said blade holding loop and including a depending flange extending downwardly from the shank for engaging one end of the blade adjacent its cutting edge and having an upwardly extending flange for engaging said end of the blade head,

said blade retaining member engaging said flanges when in an applied position.

FREDERICK W. DIERDORF.
